Primary Examiner—Susan J. Lucas*Assistant Examiner*—Jennifer Rivard*Attorney, Agent, or Firm*—Varnum, Riddering, Schmidt & Howlett LLP**[57]****CLAIM**

The ornamental large lift-up with power/data receptacles, as shown and described.

DESCRIPTION

FIG. 1 is a left side perspective view of the large lift-up with power/data receptacles according to my design. The right side perspective view is a mirror image thereof.

FIG. 2 is a front elevation view of the large lift-up with power/data receptacles according to my design. The rear elevation view is a mirror image thereof; and,

FIG. 3 is a top plan view thereof.

The broken lines are shown for illustrative purposes only and form no part of the claimed design.
